ROTARY DRIER AND DISINTEGRATOR

Allan K. Brown, Santa Cruz, Calif.

Application November 8, 1946, Serial No. 708,584

2 Claims. (Cl. 241—301)

1

This invention relates to rotary cylindrical driers, and has for its object the provision of a drier of this type in which a motor-driven blade is mounted adjacent its interior surface for the purpose of aiding in breaking up the material passing through the cylinder. Some materials which are fed to rotary driers are of a lumpy character or form lumps as they pass through the drier. In this form, the heat applied simply serves to case-harden the lumps and thereby prevent the evaporation of the moisture contained therein.

With this difficulty in mind, I have developed a rotary drier provided, as above suggested, with a blade of impeller form mounted for rotation therein adjacent its inner surface.

The invention possesses other advantageous features, some of which, with the foregoing, will be set forth at length in the following description where that form of the invention which has been selected for illustration in the drawing accompanying and forming a part of the present specification is outlined in full. In said drawing, one form of the invention is shown, but it is to be understood that it is not limited to such form, since the invention as set forth in the claims may be embodied in a plurality of forms.

Referring to the drawing:

Fig. 1 is a side elevation of a cylindrical rotary drier embodying the objects of my invention and in which parts have been broken away more readily to illustrate the invention;

Fig. 2 is a transverse section taken on the section line 2—2 of Fig. 1.

As shown in these figures, my invention has been embodied in a cylindrical rotary drier generally designated by the reference numeral 1, and which may in general be of any well-known and standard construction. The drier includes a base formed by a plurality of concrete blocks 2, 3, 4 and 5. Mounted on the blocks 2 and 5 are transversely extending and spaced channels 6, 7, 8 and 9, the upper faces of these channels being arranged to lie on a common inclined plane. Fastened to these channels adjacent the ends thereof are bearings 11 and 12, and journaled in these bearings are shafts 13, on each of which is mounted a roller 14.

Cradled on these rollers is a cylindrical sheet metal shell 15, provided on its outer surface with a pair of steel tires 16 arranged to ride on the rollers 14. Welded to the interior surface of the shell 15 are a plurality of longitudinally extending and symmetrically disposed lifting chan-

nels 17 which function in accordance with well-known practice to elevate the material passing through the cylinder.

Formed on the surface of the shell 15 are 5 one or more inwardly extending pockets 18. Welded to the shell 15 across one end of the pocket 18 is a section of angle iron 19, and fastened to this angle iron and extending into the pocket 18 is a three-phase electric motor 10 21. The shaft 22 of this motor extends through the wall of the pocket 18 into the interior of the shell 15, and mounted on the end of this shaft is a disintegrating blade 23 provided with dovetail ends. Although the axis of the motor 15 21 is radially disposed with respect to the shell 15, it can be inclined with respect thereto. If two or more motors and blades are resorted to, as shown in Fig. 1, they should be longitudinally spaced and located on different sides 20 of the shell.

Fastened to the shell 15 intermediate the two motors 21 are a plurality of insulating spacing blocks 24, and mounted on these insulating blocks are three longitudinally spaced electrical contact rings 25. The three rings 25 are each connected with one of the phases of the motor 21 through suitable leads extending through a cable 26. Mounted on the block 3 which, it will be noted, is in line with the contact 30 ring 25, is an electric brush retainer 27, in which are accommodated three spring loaded brushes 28 arranged to establish electrical contact between the three rings 25 and a cable 29 leading to a suitable source of electric current. 35 This construction therefore provides a means for energizing the motors 21 and at the same time permitting them to rotate bodily with the shell 15.

Fastened to the block 4 is an electric motor 31, 40 and mounted on the shaft of this motor is a pinion 32 arranged to mesh with and drive a ring gear 33 mounted on the outer surface of the shell 15.

In the operation of this device, the motor 31 45 rotates the shell at any desired speed about its own axis in the conventional way. The material to be dried is fed through a suitable hopper (not shown) to the left end of the shell 15 as viewed in Fig. 1. Hot air is then made to pass 50 through the cylinder in any conventional manner, although in this connection it is to be observed that the drier may be either of the direct-heat type or of the direct-indirect-heat type. Upon the rotation of the shell the material fed thereto 55 is made to progress towards the discharge end of

the shell, this being accomplished in part by the elevator channels 17 and partly by the inclination of the shell. During the progress of the material through the shell it tumbles onto the rotating disintegrating blades 23, and as a result any large lumps of the material are disintegrated, thereby providing for a far more effective heat exchange and effective evaporation of the moisture content of the material. This is of particular importance, for even though the material when fed to the drier may be in a disintegrated form if, as is usually the case, it contains an appreciable amount of moisture it will agglomerate into lumps of substantial size as a result of passing through the drier.

The motors 21 may be from two to five horsepower and, although the electric current used by them adds to the cost of the operation of the drier, this added cost is well justified by the saving of fuel effected by the use of my disintegrating vanes and which I have found to be in the order of 20%. In addition to this saving of fuel, this expedient permits the use of lower temperatures, thereby avoiding caramelizing any sugar containing products such as tomato and apple 25 pulp and grape pumice.

I claim:

1. A drier of the horizontal type comprising: a cylindrical shell mounted for rotation about a substantially horizontal axis; a motor mounted on the outer surface of said shell with its shaft extending through said shell and substantially radially thereof; a disintegrating blade mounted on the inner end of said shaft within said shell; means for energizing said motor; and means for rotating said shell about its own axis.

5 2. A rotary drier of the horizontal type comprising: a base; a cylindrical shell mounted on said base for rotation on its own axis; a disintegrating blade mounted within said shell for rotation on an axis non-parallel with the axis of said shell; an electric motor mounted on the outer surface of said shell, said motor being operatively connected to said blade; conductor rings surrounding said shell and carried thereon by insulating members, said motors being electrically connected to said conductor rings; and electric brushes mounted on said base for engagement with said conductor rings, said brushes being arranged to be connected with a source of electric current.
